COMBINATION LOCK

Peter Bolis, West Orange, N. J.

Application May 24, 1934, Serial No. 727,241

4 Claims. (Cl. 70—53)

This invention relates to combination or permutation locks, and one object of the invention is to provide such a lock embodying novel and improved features of construction whereby the lock shall be simple to operate and can be manufactured at low cost.

Another object is to provide a novel and improved combination lock including a plurality of coaxial permutation members or discs each of which has a recess to align with the recesses of the other discs when the discs are in a predetermined relation to each other, said recesses to cooperate with a locking member when they are in said predetermined relation to release the locking member which is normally held against release by abutment with the peripheries of the discs when said recesses are out of alignment, the peripheries of the discs being so formed that operation of the lock without knowledge of the combination as by clicking or operating the discs and then manually manipulating the locking member to align the recesses of the discs, shall be impossible; in other words, an important object of the invention is to provide a permutation lock which shall be substantially "pick-proof".

Other objects of the invention are to provide a permutation lock including a novel and improved construction and combination of permutation members, locking member and operating member, whereby the parts shall be simple and inexpensive in construction and can be easily and inexpensively assembled, and to obtain other advantages and results as will be brought out by the following description.

Referring to the accompanying drawings in which corresponding and like parts are designated throughout the several views by the same reference characters:

Figure 1 is a top plan view of a safe embodying a permutation lock constructed in accordance with my invention.

Figure 2 is a plan view of the door of the safe with the outer wall thereof removed and showing the locking casing in plan view.

Figure 3 is a similar view with the outer wall of the lock casing removed.

Figure 4 is a detached plan view of the underside of the outer wall of the lock casing and the permutation member mounted thereon.

Figure 5 is a view similar to Figure 4 with a portion of the spacing disc for the permutation member removed.

Figure 6 is a view similar to Figure 3 with the next partition wall of the lock removed to

expose the permutation disc beneath that shown in Figure 3.

Figures 7 and 8 are detached plan views of the bottom of the partition plate removed from Figure 6.

Figure 9 is a fragmentary view similar to Figure 3 showing the bottom wall of the lock casing with all of the permutation members and partition walls removed.

Figure 10 is an enlarged transverse sectional view through the lock and safe cover on the line 10—10 of Figure 1.

Figure 11 is an enlarged fragmentary plan view of the operating members of the lock with portions broken away to show the connection of the operating members to the permutation members.

Figure 12 is a schematic sectional view showing the connections of the operating members to the respective permutation members.

Figure 13 is an enlarged transverse sectional view on the line 13—13 of Figure 1, and

Figure 14 is a fragmentary sectional perspective view through one wall and a portion of the cover of the safe.

Specifically describing the embodiment of the invention illustrated in Figures 1 to 14, the reference character A designates the body of the safe which is approximately box-like and has a cover or door B hingedly connected to one wall at C; if desired the safe may be set into the wall of a room with only the door exposed. Preferably the walls and door of the safe are heat insulated as indicated at D. The door is shown as comprising inner and outer plates E and F between which are mounted the combination lock mechanism embodying the invention.

This lock mechanism includes two sliding bolts 1 which are movable in opposite directions and cooperate with keeper lugs 2 on the side walls of the body A. These bolts are simultaneously reciprocated in opposite directions by a pinion 3 meshed with racks 4 on the bolts and mounted on a stubshaft 5 journaled in the plates E and F and projecting through the outer plate with its outer end connected to a handle 6. One of the bolts has a pin and slot connection 7 with a block 8 pivotally mounted at 9 on the lock casing and having a stud and slot connection 10 with a locking member 110 which cooperates with permutation members and is slideable in slots 111 in the walls of the lock casing.

In the present instance, there are shown four permutation members 11, 12, 13 and 14, each of which consists of a disc of metal, and said discs are coaxially rotatable in the lock casing. As

more clearly shown in Figure 10 of the drawings the lock casing includes a bottom wall 15 secured to the inner wall F of the door of the safe, an intermediate partition plate 16, and a top plate 17 which are connected together by screws 18. The top plate 17 has a spacer disc 19 fixedly connected to the plate by a flange 20 on the disc which is secured in the plate; the permutation disc 11 is rotatably mounted between the plate 17 and the spacer disc 19. Between the spacer disc 19 and the intermediate partition wall 16 is rotatably mounted the permutation disc 12 which has an integral coaxial flange 21 projecting upwardly through the flange 20 and through the outer wall E of the door of the safe. An operating member 22 in the form of a disc has a key connection 230 with the flange 21. The permutation disc 13 is disposed between the partition wall 16 and another spacer disc 23 which has a coaxial central flange 24 projecting upwardly through the flange 21 while the last permutation disc 14 is disposed between the spacer disc 23 and the bottom wall 15 of the lock casing. This permutation disc 14 is fixedly connected to a pin 25 which projects upwardly through the flange 24 and is connected to a second operating member 26 which is in the form of a disc. It will therefore be seen that the permutation discs 12, 14 are fixedly connected respectively to the operating members 22 and 26. The permutation disc 14 has a stud and slot connection with the next adjacent permutation disc 13, which in the present instance consists of a lug 27 struck up from the disc 14 and passing through an arcuate slot 28 in the disc 13. Similarly, the permutation disc 12 has a stud and slot connection 29 with the disc 11. These connections are clearly shown in the schematic diagram of Figure 12. It will therefore be understood that the discs are arranged in two pairs and discs 14 and 12 can be rotated directly by the respective operating members 26 and 22 while the discs 13 and 11 can be operated by the operating members through the stud and slot connection with the discs 14 and 12, the discs 11 and 13 being operated by engagement of the studs with the ends of the arcuate slots. The various discs thus can be selectively operated, and the discs 14 and 12 can be operated separately from or independently of the discs 13 and 11.

Each permutation disc has a recess 30 in its periphery which can be aligned with the recesses in the other discs when the discs are in predetermined relation to each other, and the locking member 110 is movable into all of said recesses simultaneously when the recesses are so aligned. The plate 16 is formed with a notch 116 to permit the locking member to enter said recesses. Normally when the lock is in locking position, the bolts 1 are slid outwardly beneath the lugs 2 as shown in Figure 13 and the locking member 110 is withdrawn from the peripheries of the discs; and when the recesses 30 are out of alignment, movement of the locking member into releasing position is prevented by abutment thereof against the peripheries of the discs so as to prevent release or inward movement of the bolts 1 away from the lugs. By proper operation of the operating members 22 and 26 with a knowledge of the combination, the discs may be rotated to align the recesses 30 with each other, whereupon rotation of the handle 6 in the proper direction will cause the locking member 110 to be projected into the recesses, and this greater movement of the locking member thus permitted allows the bolts 1 to be

retracted from locking position, all as shown in Figure 3.

To prevent picking or clicking of the lock by manipulation of the discs and rotation of the handle 6, each disc has a plurality of notches 33 in its periphery at opposite sides of the recess 30. These notches will permit the locking member to enter them but they are so shallow that movement of the locking member is limited to less than the releasing movement permitted by the recesses 30. It will be impossible for an unauthorized person to determine whether the locking member 110 is in a notch 33 or in a recess 30, and accordingly it is impossible to align the recesses 30 without knowledge of the combination.

It will be understood by those skilled in the art that the permutation discs will be so related that the arcuate slots 28, the studs 27 and the angular relation of the operating members thereto and to the notches in the discs 13 and 12 will be such that the recesses in the disc can be aligned by rotating the operating members in certain succession in certain different directions and predetermined distances.

While I have shown and described my invention as embodied in certain specific details of construction it should be understood that this is primarily for the purpose of illustrating the principles of the invention and that many modifications and changes may be made in the structure of the lock without departing from the spirit or scope of the invention.

Having thus described my invention, what I claim is:

1. A combination lock including two pairs of coaxial relatively rotatable discs, each disc having a recess to align with the recesses of the other discs when the discs are in a predetermined relation, the discs of each pair having respectively a coaxial arcuate slot and a stud in said slot to permit movement of the discs of the respective pairs selectively relatively and together, a rotatable operating sleeve connected to one disc of one pair, and a rotatable operating pin within said sleeve connected to one disc of the other pair, whereby said recesses in the discs can be aligned by relative rotation of said sleeve and pin.

2. The combination lock set forth in claim 1 with the addition of a pair of rigidly connected spaced frame plates between which said discs are arranged, a partition plate between the two pairs of discs rigidly connected to said frame plates, and a spacer plate between the discs of each pair, said spacer plates having coaxial telescopically associated flanges extending through one of said frame plates and in which said pin and sleeve are respectively mounted.

3. The combination lock set forth in claim 1 with the addition of a pair of rigidly connected spaced frame plates between which said discs are arranged, a partition plate between the two pairs of discs rigidly connected to said frame plates, and a spacer plate between the discs of each pair, said spacer plates having coaxial telescopically associated flanges extending through one of said frame plates and in which said pin and sleeve are respectively mounted, and a locking member slidably mounted in said frame plates and normally held in locking position by abutment with the peripheries of said discs but movable into all of said recesses simultaneously into unlocking position when said recesses are in alignment.

4. A combination lock comprising a plurality of coaxial rotatable permutation disks each having a recess to align with the recess of the other

disks when the disks are in a predetermined relation to each other, a locking member normally held in locking position by abutment with said disks and movable into all of said recesses simultaneously into releasing position when said recesses are aligned with each other, and two coaxial rotatable operating members each fixedly connected to one disk, each said disk that is connected to said operating members being opera-

tively connected to another disk for movement with and relatively to the latter so that the second-mentioned disks can be rotated by rotation of the respective operating members and the corresponding first-mentioned disks can be rotated independently of the second-mentioned disks to align said recesses of all the disks.

5
PETER BOLIS.
